UNITED STATES PATENT OFFICE.

JOHN MAJER, OF LISTIE, PENNSYLVANIA.

LAMP.

1,074,442.

Specification of Letters Patent. Patented Sept. 30, 1913.

Application filed October 12, 1912. Serial No. 725,493.

To all whom it may concern:

Be it known that I, JOHN MAJER, a citizen of the United States, residing at Listie, in the county of Somerset and State of Pennsylvania, have invented certain new and useful Improvements in Lamps; and I do hereby declare the following to be a full, clear, and exact description of the invention, such as will enable others skilled in the art to 10 which it appertains to make and use the same.

This invention relates to lamps, and it relates more particularly to an improved form of miner's lamp.

15 An object of the invention is to provide an improved oil burning lamp to be used by miners, for the purpose of guarding against accidents from sparks.

Another object of the invention is to provide 20 a lamp having a reflector mounted in hinged relation to the main body of the lamp so that said reflector can quickly and easily be cleaned.

Other objects and advantages may appear 25 hereinafter and in the claims.

In the accompanying drawings, which are made a part of this application, Figure 1 is a side elevation view of my improved miner's lamp. Fig. 2 is a vertical sectional view 30 through the lamp, the burner being in elevation, and, Fig. 3 is a front elevation of the lamp.

Referring to the drawings in which similar reference numerals designate corresponding parts throughout the several views, the reference character 5 designates the reservoir or tank, for holding kerosene or any suitable liquid fuel, and to this reservoir is secured, by any proper means, as by screw 35 threads 6, a burner 7 of ordinary construction, carrying a wick 8. Secured on the burner 7 is a cylindrical combustion chamber 9, having an aperture 10 through its lower convex surface, the burner extending 40 into the combustion chamber through said aperture. Mounted or formed on the top of the combustion chamber, and communicating therewith, is the perforated crown 11, stationed concentrically above the burner 7.

45 One or more rows or series of apertures 9' are provided in the lower portion of the combustion chamber, extending around the burner, in concentric relation thereto. The

front of the combustion chamber is closed by a disk 12 of glass or other transparent material, which is held in place by means of a radially and inwardly extending flange 13, formed on a retaining ring 14, said retaining ring being secured on the combustion chamber or cylinder, by proper means, as indicated by the screw threads 15. I may provide a flat ring 16, for holding the transparent disk 12 within the ring 14 when the latter is removed from the cylinder, but it is obvious that this ring may be dispensed with if desirable. The rear end of the cylinder is closed by means of a concavo-convex door 17, hinged at 18 to the lower part of the cylinder, and provided with a latch and keeper, of any proper design, preferably a spring catch, as illustrated at 18; so that the rear end of the casing is quickly and securely closed by said door. A hook or other proper support 19 is secured on the door 17, said hook being adapted for engagement 75 with any proper support (not shown) on a miner's cap or helmet. A concavo-convex reflector 20 is snugly and securely fitted into the concavity of the door, in such relation to the flame from the burner, that the 80 light from said burner is focused approximately at the summit of the flame from the burner. It will be understood by those familiar with the art that these focused rays of light will be condensed, or intensified at 85 this point, and will tend to cross each other, but this tendency will be resisted to a considerable extent, so that the intensified or accumulated light rays will pass approximately centrally through the transparent 90 element 12, and while this transparent element will reflect the rays to some extent, the focusing effect will obtain to such an extent that a very large per cent. of the light, generated by the burner, will be concentrated 95 within working reach of the miner or user of the lamp.

The apertures 9' provide inlet openings for air, while the apertures in the crown 11 provide outlet openings for the products of combustion, and it will be seen that the passage of air between the lower and upper apertures, constitutes an uninterrupted draft, which is slightly deflected inward, or concentrated by the flame, and then passes 100 in a vertical direction into the crown 11 and

out of the outlet aperture, carrying the smoke and soot therewith. It will therefore be seen that the reflector 20 remains comparatively free from soot and smoke, so that its maximum efficiency is obtained.

- Hinged onto one side of the cylinder 9 is a trap door 21, a spring catch 22 being provided for holding the door 21 normally closed, and by means of this door, the miner 10 may relight his lamp without removing the same from its support. In thus repeatedly relighting the lamp, it occurs that the reflector 20 becomes smoked, owing to imperfect draft and incomplete combustion, 15 and so it is desirable to have easy access to the reflector for cleaning and polishing the same. This easy access is provided by means of the construction shown in which the door which carries the reflector plate may be 20 swung open; whereupon, easy access to the reflector and to the interior surface of the cylinder and of the crown is attained; so that light is reflected from the concave wall of the cylinder, as well as from the reflector. 25 The importance of keeping the crown free from soot is obvious, for the purpose of keeping the apertures thereof open, and thereby to provide a perfect draft through the combustion chamber. By hinging the 30 door 14 at the bottom, it will be seen that the hook 19 would not become disconnected, but would still retain the lamp in approximately vertical position, even if the catch 18 should become disengaged. 35 While I have described a lamp of simple construction it will be seen that I have provided one that is thoroughly practicable and efficient, and one that eliminates the danger

of falling sparks or coals, in a perfectly obvious manner.

40

I claim:

1. A lamp comprising a horizontally disposed cylindrical body having a transparent end, in combination with a burner projecting centrally into the body, a concavo-convex 45 door at the end of the body opposite to the transparent end, a hinge connecting the door at its bottom to the body, a latch at the top of the door, a reflector on the inner concave surface of the door, and a supporting hook 50 secured, point downward, to the outer convex outside of the door.

2. A lamp providing a horizontally disposed combustion chamber having openings located centrally in its upper and lower 55 sides, a burner secured in the lower opening, a crown secured in the upper opening, the walls of said crown being provided with a plurality of perforations therein, the lower side of said combustion chamber provided with a series of rows of perforations 60 therein concentric with said central opening therein, and in vertical alinement with said crown whereby air may be admitted directly into said combustion chamber and 65 burnt gases be exhausted directly through said crown.

In testimony whereof I have signed my name to this specification in the presence of two subscribing witnesses.

JOHN MAJER.
